UNITED STATES PATENT OFFICE

161,441

TELESCOPIC HOUSE TRAILER

Charles E. Grube, Arcadia, Calif., assignor to Overniter Manufacturing Corporation, Pasadena,
Calif., a corporation of California

Application September 6, 1949, Serial No. 4,862

Term of patent 7 years

(Cl. D14—3)

To all whom it may concern:

Be it known that I, Charles E. Grube, a citizen of the United States and residing at Arcadia, in the county of Los Angeles, State of California, have invented a new, original, and ornamental Design for a Telescopic House Trailer, of which the following is a specification, reference being had to the accompanying drawing, forming part thereof, in which:

Fig. 1 is a perspective view of a telescopic house trailer showing my new design, with the top part of the trailer in lowered position; the view depicting the front end and one side of the trailer.

Fig. 2 is a perspective view of the trailer depicting the rear end thereof as viewed from the side shown in Fig. 1, with the top part of the trailer in a lowered position.

Fig. 3 is a perspective view corresponding to Fig. 1 showing the top part of the trailer in extended or raised position, and

Fig. 4 is a perspective view corresponding to Fig. 2 showing the top part of the trailer in extended or raised position.

The side of the trailer opposite that depicted in the drawing substantially corresponds to the side shown.

I claim:

The ornamental design for a telescopic house trailer, substantially as shown and described.

CHARLES E. GRUBE.
